UNITED STATES PATENT OFFICE.

WILLIAM D. PARKER, OF WORCESTER, MASSACHUSETTS.

COUPLER FOR MUSICAL INSTRUMENTS.

SPECIFICATION forming part of Letters Patent No. 365,092, dated June 21, 1887.

Application filed September 20, 1886. Serial No. 214,039. (No model.)

To all whom it may concern:

Be it known that I, WILLIAM D. PARKER, a citizen of the United States, residing at Worcester, in the county of Worcester and State of Massachusetts, have invented certain new and useful Improvements in Pneumatic Couplers for Musical Instruments, of which the following, together with the accompanying drawings, is a specification, sufficiently 10 full, clear, and exact to enable persons skilled in the art to which this invention appertains to make and use the same.

The object of my present invention is to provide a simple, practical, and efficient pneumatic coupler for organs, automatic musical instruments, and similar apparatus; also, to provide, in a pneumatic coupler, means for automatically preventing the coupling effect from extending beyond the desired limit or interval 15 in the scale or range of pneumatic motors. These objects I attain by mechanism the nature of which is explained in the following description, the particular subject-matter claimed being hereinafter definitely specified.

In the drawings, Figure 1 is a vertical sectional view illustrating the nature of my improved pneumatic coupler as applied to a reed-organ or similar instrument played by a manual. Fig. 2 is a part in similar section 20 showing the coupler shut off. Fig. 3 is a section similar to Fig. 1, showing a modification of the invention or its application to an automatic musical instrument to be played by a perforated music-sheet. Fig. 4 is a part, in similar section, showing the coupler shut off. Fig. 5 is a plan diagram illustrating the manner of coupling and the arrangement of air-passages for the inlet of air to the pneumatics. Fig. 6 is a section through one of the valve- 25 chambers transversely of the passage; and Fig. 7 is a longitudinal vertical section through the wind-chest, pneumatics, valve-levers, and air-passages at line y y in Fig. 3, looking from the front in the direction indicated.

In the construction of my improved pneumatic coupler the series of pneumatic motors, otherwise called "pneumatic keys" or "pneumatic fingers," are arranged to respond to the force induced by the bellows apparatus when ever air is admitted to change the normal condition or relative pressure externally and internally of the pneumatic motor, and the sev-

eral pneumatics are provided with air-passages that lead from inlet-ducts under control of the music-sheet, manual keys, or means where- 55 by the instrument is played. These several air-inlet passages each have a branch passage leading therefrom, which communicates with the pneumatic an octave lower, (or higher,) or to such pneumatic as it is desired to couple 60 with, and at a convenient position in the course of the passages I arrange an adjustable stop, slide, or gate, whereby said branch passages can be closed or shut off, so that the air can only go to the individual pneumatic cor- 65 responding with the inlet-duct opened; or in other adjustment said passages can be opened so that the air will not only pass into the pneumatic corresponding to the note indicated, but will also at the same time pass into the pneu- 70 matic motor corresponding to the note an octave lower; (or higher, as the case may be,) and effect the expansion of the latter pneumatic motor and the consequent sounding of the octave note as well as the one indicated by 75 the music-sheet or player.

In the several air-passages, or such as may require, I arrange a series of valves that open in one direction to give free passage of air inward to the pneumatic motors, but which close 80 and resist the flow of air in the other direction. These valves serve to prevent more than a single octave or pair of pneumatics being included in the coupling effect.

In reference to parts, A designates the wind 85 chest or chamber between the reed-board A' and the bottom board, A², from which air is exhausted by suitable bellows or wind-inducing apparatus, (not shown,) connected therewith for operating in any well-known manner. 90

B indicates the sounding devices or reeds, which may be disposed in customary or any desired manner, with passages b leading into the wind-chest for the actuating air-currents, which passages are covered by the valve-pal- 95 lets c, the carrying-bars C of which are operated by the pneumatic motors D and return-springs E. In the present instance the pneumatics D are arranged within the wind-chest A, along the top board, A', in close series, and 100 corresponding in order with the valve-bars C, and in such relation thereto that the said valve-bars will severally be depressed for opening the passage and allowing the sounding devices

to act by the expansion of the pneumatic motors.

F denotes a tracker or valveway provided with a series of inlet openings or ducts, f, 5 from which passages or windways d respectively lead into the pneumatics D. Said pneumatics and ducts f correspond in number and in order with the openings, scale, or notes of the sounding devices.

10 From the passages d branch passages or auxiliary windways e extend across the interval and communicate with the pneumatic (or its inlet-passage) an octave lower (or higher) than the one corresponding with the respective passages first named.

15 The ducts f are normally closed by valves or buttons m, carried by the manual keys K, which valves are opened as the key is depressed; or in case of an automatic instrument, 20 wherein the tracker serves as a music-race, by means of the perforated music-sheet.

25 As herein illustrated, the passages d are carried backward within the board G, and then turn downward in the block H direct through the top board, A', into the pneumatics D, as indicated at d'. The branch passages e lead from the passages d upward and backward within the block H, and thence downward at a lateral inclination, as at e', and into the secondary or coupled pneumatics, or into the lower portion, d', of the passages to said secondary pneumatic. The lateral inclination and arrangement of the passages e' are indicated by dotted lines in Fig. 7.

30 Combined with the series of passages e, I employ a stop, slide, bar, or gate-piece, I, which is capable of being shifted to close off said passages e (see Figs. 2 and 4) and prevent the flow of air to the pneumatics by way of passage e, 35 or to open said passages when desired. This gate-piece I preferably consists of a bar or piece of board having formed therein openings e', corresponding to and serving as a part of the windways or passages e, which board is

40 fitted to slide on the upper part of the channel-block H, where it is held in an angular recess, or upon a suitable seating-surface, by means of springs or clips h, in such manner that it can be adjusted so that the openings e' 45 will accurately match with their respective channels e when the bar is in one position of adjustment, as indicated in Figs. 1 and 3, or when at the other position of adjustment, so that said openings and channels will offset, and thus shut off the passage of air through said channels e. (See Figs. 2 and 4.)

50 A lever, L, or device is provided for shifting the gate or bar I, which device is connected with a stop-pull, P, for operation in the manner of other musical-instrument stops, or said gate may be adjusted by any convenient means.

55 Small chambers are formed in the passages d and e, within each of which is arranged a check-valve, J, consisting, preferably, of a disk 60 of soft leather or fabric, suspended by its upper edge, so as to act as a clapper over the end of the passage, permitting free flow of air to-

ward the pneumatic, but preventing flow of air toward the tracker.

65 In Fig. 3, M indicates a perforated music-sheet for controlling the inlet of air to the ducts f. Said music may be made, mounted, and operated for acting directly as a valve for the ducts f; or, if preferred, any other well-known means for valving or controlling the inlet of air to said ducts in accordance with the musical score may be employed.

70 The operation is as follows: The bar or gate-piece I being adjusted to open the passage e, and the exhaust action of the wind-inducing mechanism being in force, then when one of the ducts f is opened a current of air rushes into said duct in response to the suction on the pneumatics. A part of the air goes by the direct passages d d' into the pneumatic D, corresponding to said duct, allowing it to explode and depress the valve C and permit the sounding of the note, and another portion of the air goes by way of the passages e e' to the coupled pneumatic, as D', thus permitting 80 said second pneumatic to explode and open the valve for sounding a note an octave away from the one indicated by the key or music-sheet. The valve J in the passages e and d prevent the backward flow of air through the 85 passages. Consequently the coupling effect cannot extend to include more than one octave or the interval represented by the pair of pneumatics.

90 In instruments wherein the coupled series does not extend beyond an octave of the scale the valves J can be omitted, as such valves are only required to prevent the continued coupling of several octaves in a long series of pneumatics.

95 The passages d and e can, if desired, be formed of tubing or in any convenient manner for connecting the tracker or key valveway and the pneumatic motors, and for connecting across the intervals from one position of the scale to its octave for coupling action, as set forth, and the pneumatics can be arranged in other location in relation to the sounding devices and wind-chest when the style of instrument or other considerations 105 render such construction more convenient.

110 What I claim as of my invention, and desire to secure by Letters Patent, is—

115 1. The combination of a series of pneumatic motors arranged for actuating the valves in a musical instrument, a tracker having a series of inlet-ducts, passages leading from the respective inlet-ducts into the respective pneumatic motors, auxiliary passages respectively connecting said inlet-passages with the pneumatics for passages thereto at a designated interval up or down the scale, a movable stop or cut-off for closing and opening said auxiliary passages, automatic devices to prevent return flow of air from the pneumatics toward the inlet-ducts, and means, substantially as described, for controlling the inlet of air to the tracker-ducts, for the purpose set forth.

120 2. The combination, in a musical instru-

ment, of a series of pneumatic motors arranged for actuating the valves which control the sounding devices, a series of inlet air-passages respectively leading into said pneumatics, the 5 manual keys having valves for stopping the inlets of said air-passages, auxiliary passages leading from inlet-passages to pneumatics an octave or designating interval, up or down the scale, the sliding stop or gate having wind- 10 ways that form a portion of said auxiliary passages, and backwardly-opening check-valves arranged in said inlet-passages between the pneumatic motors and the point of junction of the auxiliary and inlet passages to prevent 15 backward flow of air therein, substantially as and for the purpose set forth.

3. The combination of the pneumatics D,

disposed within the wind-chest at intervals of the scale, the sounding devices B and valves C, controlled by said pneumatics, the tracker 20 or valveway F, having inlet-ducts, the channel-block H, having passages d direct to said pneumatics, and the passages e, with diagonal connection across the octaves or intervals, the valves J, the stop or slide bar I, and the manual key K, with valves m, for controlling the inlet-ducts, substantially as set forth. 25

Witness my hand this 7th day of September, A. D. 1886.

WILLIAM D. PARKER.
